RAILWAY TRAFFIC CONTROLLING
APPARATUS

Herbert A. Wallace, Edgewood, Pa., assignor to
The Union Switch & Signal Company, Swiss-
vale, Pa., a corporation of Pennsylvania

Application July 17, 1934, Serial No. 735,572
Renewed October 24, 1936

18 Claims. (Cl. 246—3)

My invention relates to railway traffic controlling apparatus, and particularly to signaling apparatus for stretches of single track provided with passing sidings which apparatus is controlled in part from a remote point such as a dispatcher's office. One feature of my invention is the provision of means for reversing the established direction of traffic in a single track stretch before a train moving in one direction leaves the stretch so that an opposing train can receive its signal and enter the single track stretch without loss of time as soon as the stretch becomes unoccupied.

I will describe four forms of apparatus embodying my invention, and will then point out the novel features thereof in claims.

In the accompanying drawings, Fig. 1a is a view showing a typical layout of track and signals, and includes a diagrammatic view of the line circuits for a stretch of track to which my invention may be applied. Fig. 1b is a diagrammatic view showing the local circuits associated with signal 10 of Fig. 1a. Fig. 1c is a diagrammatic view showing the local circuits for signals R2, LA2 and LB2. Fig. 1d is a diagrammatic view showing the control circuits for back lock relays for signal R2 and for signals LA2 and LB2. Fig. 1e is a view showing a portion of the local circuits associated with signal 11. Figs. 1f and 1g are diagrammatic views showing the lighting circuits for signals LA2 and LB2, respectively. Fig. 2a is a view showing the same layout of track and signals as Fig. 1a but showing the line circuits as arranged to illustrate a modified form of my invention. Fig. 2b illustrates a modification of a portion of the circuits of Fig. 1b employed with the modified form of my invention illustrated in Fig. 2a. Fig. 3 is a view showing the same layout of track and signals as Fig. 1a, but with the circuits arranged to show a third form of my invention. Fig. 4 is a view showing how my invention may be employed when staggered intermediate signals are used.

Similar reference characters refer to similar parts in each of the several views.

In order to simplify the drawings and to enable the circuits to be more readily traced, the track switch and each signal shown in the drawings has been identified by a number and each relay by a letter, or combination of letters, with a numerical prefix identifying the switch or signal with which the relay is associated. The various relay contacts referred to herein are identified by number, and those contacts not adjacent the respective relays which operate them bear the reference

characters for the respective relays as well as the numbers identifying the contacts.

Referring to Fig. 1a, the track diagram at the top illustrates a typical portion of a single track stretch of railroad having the opposing intermediate signals 10 and 11 and opposing head block signals R2 and LA2 or LB2. This stretch includes a switch section 1T containing a track switch 1 and provided with the usual detector track circuit having a track relay 1TR, and also includes a single track portion divided into a plurality of sections, of which only the sections 2T, 10T and part of 11T are shown, these sections being provided with the usual track circuits having track relays 2TR, 10TR and 11TR, respectively. Traffic moving toward the right into this stretch of track is governed by the automatic signal 10 which is one of the usual intermediate block signals of an absolute permissive block signaling system, while traffic moving toward the left is governed by the head block signals LA2 and LB2 according as switch 1 is in its normal or reverse position. Signals LA2 and LB2 are controlled in part from a remote point such as a dispatcher's office and are also controlled in part by the track relays of the stretch and by apparatus associated with the automatic signals 10 and 11. The opposing head block signal R2 governs traffic moving toward the right out of section 2T, and the automatic signal 11 governs traffic moving toward the left out of section 10T. Signal 10 is controlled by a slow pick up, slow release repeater relay 10HP shown in Fig. 1b, which relay is in turn controlled by a polarized line relay 10H, while the opposing signal 11 is similarly controlled by a corresponding relay 11HP, shown in Fig. 1e, which is in turn controlled by a line relay 11H. In considering the circuits herein disclosed, it is to be understood that a local source of current is provided at each signal location, but for simplicity the circuits have been illustrated diagrammatically, and instead of showing the local sources and the wires leading thereto in detail only the terminals of the sources are shown, these being designated in each case by the reference characters B and C. Assuming that relay RA2H shown in Fig. 1c, for controlling arm A of signal R2 is energized, the circuit for relay 10H shown in Fig. 1a may be traced from terminal B of a suitable source of current, through pole-changer 50 contact 2 operated by relay RA2H, back contact 3 of the manually controlled relay L2HS of Fig. 1c, back contact 4 of the line relay L2H for controlling signals LA2 and LB2, front contact 5 of relay L2GP of Fig. 1d, front contacts 6 and 7 of 55

track relays 1TR and 2TR, respectively, wire 8, front contact 9 of track relay 10TR, relay 10H, front contact 12 of relay 10TR, wire 13, pole-changer contact 14 of relay RA2H to terminal C 5 of the same source of current.

Relay L2GP, which has a contact 5 in the circuit just traced, is a back lock relay for signals LA2 and LB2 having a circuit including back contacts of the signal relays LB2H and LA2H 10 as shown in Fig. 1d, and relay L2GP is energized when signals LA2 and LB2 indicate stop. It follows, therefore, that the circuit for relay 10H is open when a train occupies any part of the stretch between signals 10 and LA2, or when relays L2H or L2HS are energized, and that the polarity of current supplied to relay 10H is determined by the position of relay RA2H.

As indicated in Fig. 1c, relay RA2H is controlled by a line relay R2H which it is to be understood is controlled by conditions in the main line stretch to the right of section 1T, and by a manually controlled relay R2HS, and becomes energized only when traffic conditions are such as to permit signal R2A to properly indicate caution 25 or clear. Referring to Fig. 1b, the circuit for relay 10HP includes a front contact 15 of relay 10H so that the slow pickup repeater relay 10HP becomes energized at the end of its time period after relay 10H is energized, and releases at the 30 end of its release period after 10H releases. Relay 10HP is the usual slow pickup slow release relay associated with an intermediate signal of an absolute permissive block signaling system, and together with the relay 10H, as is clear from 35 Figs. 1a and 1b, controls the signal lamps G, Y and R of signal 10 in such a manner that lamp R will be lighted to cause signal 10 to display a stop indication when any portion of the stretch between signal 10 and the opposing signal L2A 40 or L2B is occupied, lamp Y will be lighted to cause the signal to indicate caution when the stretch is unoccupied and relay RA2H is deenergized, and lamp G will be lighted to cause the signal to indicate proceed when the stretch is 45 unoccupied and relay RA2H is energized. Relay 10S in Fig. 1b is the usual directional stick relay associated with the intermediate signal 10, and is provided with a pickup circuit which may be traced from terminal B, back contact 16 of an auxiliary relay 10Z shown in Fig. 1a, back contact 17 of track relay 10TR, front contact 18 of relay 10HP, relay 10S to terminal C, and which becomes closed when a train moving toward the right passes signal 10 at clear or caution. Relay 10S is provided with a stick circuit which may be traced from terminal B, back contact 16 of relay 10Z, back contacts 17 and 18 of relays 10TR and 10HP in multiple, front contact 19 and winding of relay 10S to terminal C, so that when relay 10S once becomes energized it will remain picked up as long as relays 10HP and 10Z remain deenergized. Relays 10S and 10HP together control the energization and polarity of current supplied to the circuit comprising wires 8' and 13' for controlling the next signal in the rear of signal 10, not shown, for governing traffic moving toward the right toward signal 10, by means of contacts 20, 21 and 22. Relay 11S 65 is the corresponding directional stick relay for signal 11 and its circuits as shown in Fig. 1e, are similar to those for relay 10S except that they do not include a contact of an auxiliary relay such as relay 10Z, an auxiliary relay being not needed for the control of an intermediate section 70 such as that governed by signal 11. Relays 11S

and 11HP together control the energization and polarity of current supplied to the circuit for line relay L2H.

Referring to Fig. 1a and assuming that relay 11HP is energized, the circuit for the line relay L2H for controlling signals LA2 and LB2 is from terminal B, pole-changer contact 23 of relay 11HP, front contacts 24 and 25 of relays 11S and 11S in multiple, back contacts 26 and 27 of relays 10HP and 10S, respectively, front contact 28 of track relay 10TR, wire 29, back contacts 30 and 31 of the manually controlled relays L2HSP and L2HS, front contact 32 of relay 2TR, relay L2H, front contact 33 of track relay 2TR, wire 13, front contact 12 of relay 10TR, pole-changer contact 34 of relay 11HP to terminal C of the same source of energy, so that relay L2H is energized when the portion of the stretch between signals 10 and R2 is unoccupied and relays 10HP and 10S are deenergized, provided either the section to the left of signal 11 is occupied by a train moving toward the left so that relay 11S is energized or provided that section is unoccupied and relay 11HP is energized.

Referring to Fig. 1c, the manual control of the signals is effected through the medium of a pair of selector contacts L and R, one or the other of which may be selectively closed to establish the left-hand or right-hand direction of traffic, and by a delivery relay D which may be momentarily energized, by manual control from a remote point, such as a dispatcher's office, through the medium of a centralized traffic control system. When relay D is operated, it controls a pair of stick relays, R2HS and L2HS, in accordance with the position of a signal lever located in the dispatcher's office. As illustrative of such control, the signal lever, identified by the legend "Sig", is shown connected by dotted lines to contacts L and R, and it is to be understood that contact L or R may be closed by moving the signal lever to the left or right, respectively, from its normal position, as shown. In order to clear signal LA2 or LB2 to permit the movement of traffic toward the left through the stretch, the operator at the dispatcher's office will by remote control close contact L and then momentarily energize relay D, thereby opening contact 35 in the stick circuits of relays R2HS and L2HS, and completing a pickup circuit from terminal B, contact L, contact 36 of relay D, relay L2HS to terminal C, so that relay L2HS will become energized. When relay D releases, the stick circuit of relay L2HS is closed from terminal B, back contact 35 of relay D, front contact 37 of relay 1TR, back contact 38 of relay R2HS, front contact 39 and winding of relay L2HS to terminal C. When a train enters section 1T, relay 1TR releases and opens contact 37 thereby releasing relay L2HS. Relay 1TR is provided with a slow acting repeater relay 1TZ which has a back contact 40 in multiple with contact 37, which becomes closed when the stick circuit of L2HS has been opened for a time sufficient to insure its release. It follows that relay D may be operated to pick up relay L2HS even though section 1T is occupied, and the stick circuit for L2HS will then be completed over the back contact 40 of relay 1TZ as is obvious from the drawings.

Relay L2HS controls a slow pick up slow release repeater relay L2HSP, and when relay L2HS becomes energized, if section 2T is unoccupied, a circuit will be closed from terminal B, front contacts 41 and 42 of relays L2HS and 2TR, relay L2HSP to terminal C. Assuming that sig- 75

nal R2 is at stop, relay R2GP is energized over the circuit shown in Fig. 1d, which may be traced from terminal B, back contact 43 of relay 10HP and reverse polar contact 44 of relay 10H in 5 multiple, back contacts 45 and 46 of signal relays RB2H and RA2H, relay R2GP, to terminal C. When relay L2HSP is energized, a circuit shown in Fig. 1c is closed from terminal B, front contact 47 of relay R2GP, back contact 48 of relay R2HS, 10 front contacts 49, 50 and 51 of relays 10TR, L2HSP and L2H, respectively, front neutral contact 52 and normal polar contact 53 of the switch indication relay 1KR for switch 1 (closed only when switch 1 is closed and locked in its normal position), relay LA2H to terminal C. When relays LA2H and L2H are energized, signal LA2 will display a caution or a proceed indication, as will be obvious from Fig. 1f, which shows in detail the lighting circuits for signal LA2. If the switch is 20 closed and locked reversed, relay 1KR will be energized in the reverse direction so that the right-hand contact 53 will be closed and in that case signal relay LB2H will be energized instead of relay LA2H to cause signal LB2 to indicate caution or proceed, as will be clear from Fig. 1g.

The circuit for relay L2H, as hereinbefore described, includes back contacts 30 and 31 of the manually controlled relays L2HSP and L2HS, and when relay L2HS is picked up, this circuit is 30 opened at back contact 31. However, when relay L2HSP picks up, contact 31 is bridged by front contact 38 of relay L2HSP so that the circuit for relay L2H will again become closed. During the interval when relay L2HS is picked up 35 and relay L2HSP is in the release position, if relay 10S is energized at the time, a circuit is closed from terminal B, back contact 14 of relay RA2H, wire 13, front contact 12 of track relay 10TR, relay 10Z, front contact 27 of relay 10S, front 40 contact 28 of relay 10TR, wire 29, back contact 39 of relay L2HSP, front contact 31 of relay L2HS, resistor 63, back contact 2 of relay RA2H to terminal C. When 10Z picks up, its back contact 16, shown in Fig. 1b, opens the stick circuit 45 of relay 10S, so that relay 10S will become released.

Assuming that a train moving toward the right is approaching signal 10, the operation of the apparatus of Figs. 1a to 1g, inclusive, is as follows: 50 Since signal 11 is governed by the section occupied by the train, it will be at stop, and relays 11HP and 11S will be deenergized, so that relays L2H, LA2H and LB2H will be deenergized. Therefore, relays R2GP, 10H and 10HP may be 55 energized so that signal 10 will indicate caution or proceed. When the train passes signal 10, relays 10TR, 10H and 10HP will release consecutively, so that relay 10S will become energized, closing its front contact 22 to complete the line 60 circuit including wires 8' and 13' for the next signal in the rear of signal 10 to permit that signal to indicate caution, thereby maintaining the established direction of traffic as long as relay 10S remains energized. When the train passes 65 out of the block section so that relay 10TR picks up, relay 10H will again become energized, and at the end of its time period relay 10HP will pick up and release 10S.

Assuming now that the operator at the dispatcher's office is provided with the usual "OS" 70 indication means for indicating the condition of the switch section 1T, that the stretch is occupied by a train moving toward the right and approaching arm A of signal R2 at clear, and that an opposing train occupies the passing siding and is 75

approaching signal LB2; as soon as the operator is informed that the train moving toward the right has entered section 1T, he will operate his control apparatus to close contact L and to pick up relay D to cause stick relay L2HS to become 5 energized. Relay L2HS will pick up and will be held energized over its stick circuit including back contact 40 of relay 10Z as already described. Even though the rear portion of the train moving toward the right still occupies section 2T, the 10 closing of front contact 31 of relay L2HS will cause relay 10Z to pick up to release stick relay 10S. The release of relay 10S opens the circuit for the next signal in the rear of signal 10 governing traffic moving toward the right to return this 15 signal from the caution to the stop position. The signal relay for the latter signal, in turn, will open the circuit for the next signal in the rear of that signal in accordance with the usual tandem control of the signals employed in the absolute permissive block system, thereby cancelling the established direction of traffic and permitting the opposing signals for governing the movement of traffic toward the left up to and including signal 20 11 to be cleared. Relay 11HP, released when the 25 opposing traffic direction was established, will therefore now become energized, and since back contact 27 of relay 10S is now closed, when the train moving toward the right passes out of section 2T, and relay 2TR picks up, relays L2HSP and L2H will become energized. As soon as the train passes out of section 1T, switch 1 may be reversed by the operation of the remote control apparatus to effect the closing of the circuits shown in Figs. 1c and 1g for clearing signal LB2 just as soon as 30 the switch completes its movement to its reverse position and the neutral contact 52 and right-hand polar contact 53 of relay 1KR becomes closed.

When the train moving toward the right passes 40 out of section 1T, the energization of relays 10H and 10HP and the consequent opening of back contact 26 in the circuit of relay L2H is prevented because the circuit of relay 10H includes back contact 3 of relay L2HS, which relay is now energized. 45

Assuming now that relay 10Z embodying my invention is omitted, and that the only way to release relay 10S is by picking up relay 10HP, it will be evident that the operator must delay 50 his energization of relay L2HS to reverse the traffic direction until sufficient time has elapsed after the train moving toward the right has passed out of section 1T to permit relays 10H and 10HP to pick up, in order to release 10S, 55 and if relay L2HS is then picked up, a delay which in practice may amount to several seconds may occur before relay 10HP releases to deenergize the corresponding relay for the next signal in the rear, and the cumulative delay occurring 60 before signal LB2 can be cleared may be prohibitive and such as to preclude the effecting of a meet without stopping and delaying the opposing train approaching signal LB2.

By the practice of my invention, this delay 65 is wholly avoided, the cancellation of the established direction of traffic is effected while the stretch is still occupied so that the signal for the opposite direction may be cleared with a minimum delay as soon as the stretch becomes unoccupied. 70

Referring again to Fig. 1a, the circuits therein shown include in addition to those already described, a circuit including wires 54 and 13 for controlling an approach relay R2AR which forms 75

no part of my present invention but which is employed to indicate when a train is approaching the switch section $1T$.

Referring now to the modification of my invention shown in Figs. 2a and 2b, the circuits of this form of my apparatus are generally similar to those of Figs. 1a to 1g, inclusive, but it is to be understood that in this modified form Fig. 2a is to be substituted for Fig. 1a and Fig. 2b for the corresponding portion of Fig. 1b. In this modified form of my apparatus, instead of using the circuit of the signal relay L2H comprising wires 29 and 13 for controlling the relay 10Z, the circuit of the approach relay R2AR above referred to is employed to control a relay 10Z' which is connected in this circuit in series with relay R2AR. The circuit for relays R2AR and 10Z' is from terminal B, front contact 23 of relay 11HP, front contact 55 of track relay 11TR, relay 10Z', front contact 56 of track relay 10TR, wire 54, back contacts 57 and 58 of relays L2HSP and L2HS, front contact 59 of track relay 2TR, resistor 60, asymmetric unit 61, relay R2AR, asymmetric unit 62, front contact 33 of relay 25 2TR, common return wire 13, front contact 12 of relay 10TR, front contact 34 of relay 11HP, to terminal C. In the event a train moving toward the right approaches or passes signal 10, the circuit for relays R2AR and 10Z' will be open 30 due to the release of relay 10TR or 11TR so that back contact 16 of relay 10Z', included in the pickup and stick circuits of relay 10S as shown in Fig. 2b, will be closed. It follows, therefore, that relay 10S may be energized in the usual 35 manner. If, now, the operator picks up relay L2HS when a train moving toward the right enters section $1T$, as already described, relay 11HP being deenergized, a circuit for relay 10Z' will be closed as soon as the train passes out of section 40 10T, which may be traced from terminal B, back contact 34 of relay 11HP, front contact 12 of relay 10TR, wire 13, resistor 64, front contact 58 of relay L2HS, back contact 57 of relay L2HSP, wire 54, front contact 56 of relay 45 10TR, relay 10Z', front contact 55 of relay 11TR, back contact 23 of relay 11HP to terminal C, so that 10Z' may be picked up to release relay 10S under the same conditions and in the same manner as already described in connection 50 with the similar relay 10Z of Fig. 1a.

In the arrangement shown in Fig. 2a, relay L2HSP is picked up when section 2T becomes unoccupied, as in the first form of my invention and will then close its front contact 57 and thus 55 restore the circuit for energizing relay R2AR.

In the forms of my invention illustrated in Figs. 3 and 4, a saving of apparatus is effected by the elimination of the repeater relay L2HSP, and relay 10S is released by relay 10Z not merely 60 when traffic is to be reversed, but when the existing traffic direction is to be maintained as well, and the circuits are arranged to employ wires 8 and 13 for the control of relay 10Z. To simplify the drawings, the circuits for relay R2AR 65 have been omitted from these views.

The signal layout and the system of Fig. 3 are to be understood as being the same as that of Figs. 1a to 1g, inclusive, except that Fig. 3 is to be substituted for Fig. 1a and for that portion of Fig. 1b showing the connections to wires 8' and 13' for controlling the next signal in the rear of signal 10 for the same direction, and it is also to be understood that relay L2HSP is omitted and that a contact of relay L2HS is to 70 be substituted for contact 50 in Fig. 1c.

Referring to Fig. 3, the circuit of relay 10H includes a back contact 65 of relay 10S, so that when a train moving toward the right passes signal 10, and relay 10S picks up, the circuit of relay 10H will be opened. Since the established direction of traffic in the portion of the stretch in the rear of the train is maintained as long as relay 10S is energized, it follows that the circuits for the opposing signals will be held open and therefore relay 11HP will be deenergized. If now the operator wishes to reverse the traffic direction and picks up relay L2HS when the train enters section $1T$, as already described, a circuit for relay 10Z will be closed as soon as the train passes out of section 10T, which may be traced from terminal B, back contact 34 of relay 11HP, contact 12 of relay 10TR, wire 13, front contact 3 of relay L2HS, wire 8, contact 9 of relay 10TR, front contact 65 of relay 10S, relay 10Z, back contact 23 of relay 11HP to terminal C. Relay 10Z will therefore pick up and open its back contact 16, Fig. 1b, to release relay 10S, permitting a prompt reversal of traffic as soon as the train passes out of the stretch, as hereinbefore described in connection with Fig. 1a. If, however, the operator wishes to maintain the existing traffic direction from left to right and therefore does not pick up relay L2HS, a circuit will be closed when the train passes out of the stretch and relay 11TR picks up, which may be traced from terminal B of the source adjacent signal 11, back contact 34 of relay 11HP, contact 12 of relay 10TR, wire 13, contact 33 of relay 2TR, back contact 2 of relay RA2H to terminal C of the source of current adjacent signal R2, through this source in series to its terminal B, back contacts 14 and 4 of relays RA2H and L2H, front contacts 5, 6 and 7 of relays L2GP, 1TR and 2TR, respectively, back contact 3 of relay L2HS, wire 8, contact 9 of relay 10TR, front contact 65 of relay 10S, relay 10Z, back contact 23 of relay 11HP to terminal C. It will be noted that the polarities of the two sources in the circuit just traced are additive, because the pole-changing relays 11HP and RA2H are both deenergized when the circuit for relay 10Z is closed. Relay 10Z will therefore pick up and release relay 10S, and when relay 10S closes its back contact 65, relay 10H will become energized from the source adjacent signal R2 over a portion of the circuit just described, which does not include the source adjacent signal 11. Since in this instance the existing traffic direction is to be maintained, it is desirable to avoid a momentary opening of the caution control circuit for the signal in the rear of signal 10 including wires 8' and 13', due to the opening of contact 22 of relay 10S before relay 10HP picks up to close its front contacts 20 and 21. This is accomplished by bridging contact 22 of relay 10S by contacts 66 and 67 of relays 10Z and 10H, respectively, as shown in the drawings, and by making relay 10Z a slow release relay, when necessary.

As will be clear from the drawings, the system of Fig. 4 is the same as that of Fig. 3, except for those changes rendered necessary by the staggered location of the intermediate signals 10 and 11. In Fig. 4, the source of energy adjacent signal 11 is not available at signal 10, and hence the source adjacent the latter signal 70 is employed to control relay 10Z. Referring to Fig. 4, and assuming as before that the operator picks up relay L2HS when a train moving toward the right has entered section $1T$ and that relay 10S is picked up, a circuit for relay 10Z will be 75

closed as soon as the train passes out of section 10T which may be traced from terminal B, front contact 22 of relay 10S, back contact 21 of relay 10HP, wire 13', contact 66 of relay 11TR, wire 5 67, contact 12 of relay 10TR, wire 13, front contact 3 of relay L2HS, wire 8, contact 9 of relay 10TR, back contacts 67 and 68 of relays 11S and 11HP, wire 69, contact 70 of relay 11TR, front contact 65 of relay 10S, relay 10Z, wire 8', back contact 20 of relay 10HP to terminal C. Relay 10Z will therefore pick up and cause the release of relay 10S, permitting a prompt reversal of traffic in the same manner as in the other forms of our invention hereinbefore described. In Fig. 10 15 4, when relay 10S is picked up, if the existing traffic direction is to be maintained and relay L2HS is deenergized, the connection from wire 13 to wire 8 over front contact 3 of relay L2HS in the circuit just described will be open, but a 20 branch around front contact 3 in the circuit of relay 10Z will be closed from wire 13, contact 33 of relay 2TR, back contact 2 of relay RA2H, terminal C of the source adjacent signal R2, through this source to its terminal B, back contacts 14 and 4 of relays RA2H and L2H, front contacts 5, 6 and 7 of relays L2GP, 1TR and 2TR, respectively, back contact 3 of relay L2HS, to wire 8, so that relay 10Z will become energized to release the directional stick relay 10S. In this 25 30 instance also the H relay for the signal in the rear of signal 10 which is energized over line wires 8' and 13' from the source adjacent signal 10, is maintained energized from the time relay 10Z picks up until relay 10HP picks up, by means 35 of contacts 66 and 67 of relays 10Z and 10H which bridge contact 22 of relay 10S. It will be evident from the foregoing, therefore, that the 40 operation of that form of my apparatus illustrated in Fig. 4 is the same as that of the apparatus of Fig. 3.

Although I have herein shown and described but a few forms of apparatus embodying my invention, it is understood that various changes and modifications may be made therein within 45 the scope of the appended claims without departing from the spirit and scope of my invention.

Having thus described my invention, what I claim is:

50 1. In a block signaling system for railroads, a signal at one end of a block section, a line relay governed by traffic conditions in said section for controlling said signal, a directional stick relay, means energizing the directional stick relay when a train governed by said signal enters the section at said one end, means controlled by the line relay for holding said relay energized as long as such train remains in the section, a manually controlled relay, means effective when said 55 manually controlled relay is energized to release said directional stick relay before said train leaves the block section, and means controlled by the directional stick relay when energized for controlling the direction of train movements into said block section.

65 2. In a block signaling system for railroads, a signal at one end of a block section, a line relay governed by traffic conditions in said section for controlling said signal, a directional stick relay, means for energizing the directional stick relay when a train governed by said signal enters the section at said one end, means controlled by the line relay for holding said relay energized as long as such train remains in the section, a manually 70 controlled relay, means effective when said di-

rectional stick relay is energized to maintain the existing direction of traffic in said block section, and means effective when said manually controlled relay is energized to release said directional stick relay and to establish the opposite 5 direction of traffic in said block section.

3. In a block signaling system for railroads, a block section, a line relay, means deenergizing the line relay when said block section is occupied, a repeater relay controlled by said line relay for governing the movement of traffic in one direction into said block section, a manually controllable relay, a directional stick relay, a pickup circuit for said directional stick relay controlled by a front contact of said repeater relay and by 10 traffic conditions in said block section, a stick circuit for said directional stick relay controlled by back contacts of said repeater relay and of said manually controllable relay, and means effective when said directional stick relay is energized to maintain the existing direction of traffic 15 in said block section.

4. In a block signaling system for railroads, a block section, a line relay controlled by traffic conditions in said section, a slow acting repeater 25 relay controlled by said line relay for governing the movement of traffic in one direction into said block section, a directional stick relay, means energizing the directional stick relay when a train enters the section in said one direction, a stick circuit for holding said directional stick relay energized as long as the block section is occupied including a back contact of said repeater relay, a second line relay controlled by traffic conditions 30 in said section and by a back contact of said directional stick relay for governing the movement of traffic in the opposite direction into said block section, manually controlled means for selectively controlling said line relays, and means effective 35 when said manually controlled means is operated to release said stick relay even though a portion of said block section is occupied, and to cause said second line relay to become energized as soon as said block section becomes unoccupied.

5. In a block signaling system for railroads, an intermediate signal for governing the movement of traffic in one direction into a block section, a line relay energized only when said block is unoccupied for controlling said signal, a directional stick relay for governing the movement of traffic approaching the block section in said one direction, means for energizing said directional stick relay when a train governed by said signal enters the block section, a stick circuit for said directional stick relay including a back contact closed when said line relay is deenergized, manually controlled means for preventing the energization of said line relay when the block section becomes unoccupied, and means controlled by said manually controlled means for opening said stick circuit to release said directional stick relay even though said line relay remains deenergized.

6. In a block signaling system for railroads, an intermediate signal for governing the movement of traffic in one direction into a block section, a manually controlled signal for governing the movement of traffic in the opposite direction into said block section, a line relay for each signal controlled by traffic conditions in said block section, manually controlled means for selectively 65 controlling said line relays to permit the signal for but one traffic direction to be cleared at a time, a directional stick relay so controlled as to become energized when a train governed by the intermediate signal enters the block section and 70 75

effective when energized to prevent the clearing of the opposing signal, means for releasing said stick relay provided said manually controlled means is in condition to maintain the traffic direction existing when said stick relay became energized, and other means for releasing said stick relay effective when said manually controlled means is operated to reverse said traffic direction.

10 7. In a block signaling system for railroads, an intermediate signal for governing the movement of traffic in one direction into a block section, a line relay governed by traffic conditions in said block section and effective when energized to clear said signal, a directional stick relay so controlled as to become energized when a train governed by said signal enters the block section, means controlled by said line relay for thereafter maintaining said directional stick relay energized 15 as long as said line relay is deenergized, an opposing signal for governing the movement of traffic in the opposite direction through said block section, control means effective when operated to clear said opposing signal provided the line relay 20 and the directional stick relay are deenergized, said control means including means for maintaining the line relay deenergized irrespective of traffic conditions in said block section, and means 25 independent of the line relay for releasing the 30 directional stick relay.

8. In a block signaling system for railroads, an intermediate signal for governing the movement of traffic in one direction into a block section, a head block signal for governing the movement of traffic in the opposite direction into said block section, a manually controlled selector for controlling the signals to select the direction of traffic movement into the block section, a directional stick relay energized automatically when 35 a train passes the intermediate signal to enter the block section and effective when energized to maintain the existing traffic direction, means for maintaining said directional stick relay energized until the train leaves the block section, and 40 means controlled by said selector for releasing said stick relay to cancel the existing traffic direction before said train leaves the block section.

9. In a block signaling system for railroads, an intermediate signal for governing the movement of traffic in one direction into a block section, a head block signal for governing the movement of traffic in the opposite direction into said block section, manually controlled means for selecting the traffic direction, a directional stick relay energized automatically when a train passes the intermediate signal to enter the block section and effective to maintain the existing traffic direction as long as said relay is energized, and means effective before said train leaves the block section to 50 release said relay provided the manually controlled means has been operated to reverse the traffic direction.

10. In a block signaling system for railroads, a line relay for governing the movement of traffic in one direction into a block section, an auxiliary relay, a directional stick relay for governing the movement of traffic approaching the block section in said one direction, a pickup circuit for said 55 directional stick relay controlled by said line relay and closed when a train moving in said one direction enters the block section, a stick circuit for said directional stick relay including a back contact of said auxiliary relay and a back contact controlled by said line relay, and an energizing 60

circuit for said auxiliary relay including a front contact of said directional stick relay.

11. In a block signaling system for railroads, a line relay for governing the movement of traffic in one direction into a block section, an auxiliary relay, a directional stick relay for governing the movement of traffic approaching the block section in said one direction, a pickup circuit for said directional stick relay controlled by said line relay and closed when a train moving in said one direction enters the block section, a stick circuit for said directional stick relay including a back contact of said auxiliary relay, an energizing circuit for said auxiliary relay including a front contact of said directional stick relay, means normally effective to close said energizing circuit when the train moves out of said block section, and manually controlled means for closing said energizing circuit before the train moves out of said section.

12. In a block signaling system for railroads, a line relay for governing the movement of traffic in one direction into a block section, an auxiliary relay, a directional stick relay for governing the movement of traffic approaching the block section in said one direction, a pickup circuit for said directional stick relay controlled by said line relay and closed when a train moving in said one direction enters the block section, a stick circuit for said directional stick relay including a back contact of said auxiliary relay, a manually controlled relay for governing the movement of traffic in the opposite direction into said block section, an energizing circuit for said line relay including a back contact of said manually controlled relay, and an energizing circuit for said auxiliary relay including front contacts of said directional stick relay and of said manually controlled relay.

13. In a block signaling system for railroads, a line relay for governing the movement of traffic in one direction into a block section, an auxiliary relay, a directional stick relay for governing the movement of traffic approaching the block section in said one direction, a pickup circuit for said directional stick relay controlled by said line relay and closed when a train moving in said one direction enters the block section, a stick circuit for said directional stick relay including a back contact of said auxiliary relay and a back contact controlled by said line relay, and means including a line circuit closed when said block section becomes unoccupied for energizing said auxiliary relay.

14. In a block signaling system for railroads, a signal at one end of a block section, a line relay governed by traffic conditions in said section for controlling said signal, a directional stick relay, means for energizing the directional stick relay when a train governed by said signal enters the section, means controlled by the line relay for holding the directional stick relay energized to maintain the existing traffic direction as long as the train remains in the block section, a manually controlled relay having a back contact in the energizing circuit of said line relay, and means effective when said manually controlled relay is energized to release said directional stick relay.

15. In a block signaling system for railroads, two signals, one at each end of a block section for governing the movement of traffic into said section, means controlled in accordance with traffic conditions in said section for clearing one of said signals, a directional stick relay, means energizing said relay when a train enters the block section under the control of said one signal, slow- 70

acting means holding said relay energized as long as such train remains in the block section and for a predetermined time interval after it leaves the section, a manually controlled relay, means releasing the directional stick relay before such train leaves the block section if the manually controlled relay is energized, and means effective if the manually controlled relay is energized and the directional stick relay is deenergized for clearing the other signal in accordance with traffic conditions in said section.

16. In a block signaling system for railroads, two signals, one at each end of a block section for governing the movement of traffic into said section, means controlled in accordance with traffic conditions in said section for clearing one of said signals, a directional stick relay, means energizing said relay when a train moving in one direction enters the block section under the control of said one signal, slow-acting means holding said relay energized as long as such train remains in the block section and for a predetermined time interval after it leaves the section, means controlled by the directional stick relay for maintaining the established direction of traffic as long as such relay is energized, a manually controlled relay, means effective when said manually controlled relay is energized for clearing the other signal in accordance with traffic conditions in said section provided the directional stick relay is deenergized, and means controlled by said manually controlled relay for deenergizing said directional stick relay while the block section is still occupied to effect the clearing of said other signal as soon as the stretch becomes unoccupied.

17. In a block signaling system for railroads, a block section including two track sections, two signals, one at each end of said block section for governing the movement of traffic into said block section, means controlled in accordance

with traffic conditions for clearing one of said signals, a directional stick relay, means energizing said relay when a train enters the block section under the control of said one signal, slow-acting means holding said relay energized as long as such train remains in the block section and for a predetermined time interval after it leaves the block section, a manually controlled relay, means releasing the directional stick relay if the manually controlled relay is energized and the train has vacated one of said track sections, and means effective if the manually controlled relay is energized and the directional stick relay is deenergized for clearing the other signal as soon as the train vacates the other track section.

18. In a block signaling system for railroads, a block section including two track sections, two signals one at each end of said block section for governing the movement of traffic into said block section, a manually controlled relay, a line relay, means energizing the line relay only when the manually controlled relay is deenergized and both said track sections are unoccupied, a slow-acting repeater relay controlled by the line relay effective when energized to clear one of said signals, a directional stick relay, a pickup circuit for said directional stick relay including a front contact of said repeater relay and a contact closed when one of said track sections is occupied, a stick circuit for said directional stick relay including a back contact of said repeater relay, means effective if the manually controlled relay is energized and said repeater relay and directional stick relay are both deenergized for clearing the other signal in accordance with traffic conditions in said block section, and means releasing the directional stick relay if the manually controlled relay is energized and said one track section is unoccupied.

HERBERT A. WALLACE.
